UNITED STATES PATENT OFFICE

CLIFFORD H. GREEN, OF GRAND RAPIDS, MICHIGAN

STARTING AND SELECTING MECHANISM FOR AUTOMATIC MUSICAL INSTRUMENTS

Application filed September 15, 1921. Serial No. 500,802.

My invention relates to improvements in coin-controlled electric and mechanical means for actuating the motor circuit and selective mechanism of an electrically driven mechanical musical instrument, such as an automatic pneumatic player piano, which is adapted to selectively play a plurality of music rolls, the selection depending upon the coin chute in which the coin is deposited.

10 The primary aim of this invention is to combine in a compact, comparatively simple and efficient structure, easily installed in a player piano, for instance, means for mechanically actuating the electric switch for starting the motor and for controlling the operation of said means and the selection of a roll or rolls to be played by the insertion of a coin or coins in a series of coin-chutes; means for restoring the respective coin controlled 15 selecting means to normal position after each roll has been selected; and means for opening the switch, and restoring all of the parts of said switch actuating means to their normal positions when the playing of the selected roll or rolls has been completed.

It is well known to those skilled in the art, that automatic player pianos, which play the music roll selected, usually include a rotatable magazine or otherwise operable frame 20 carrying a plurality of rolls from which the selection is made, these rolls, depending upon the coin slot in which the coin is deposited, being successively or otherwise brought into operative relation with the 25 tracker-bar and fed over this bar in the usual manner.

Heretofore, in musical instruments of this character having a plurality of perforated music rolls, the roll that was selected could 30 be played by depositing a suitable coin in the selected coin-chute, which chute constituted the initial element of the respective train of mechanical and electrical devices that were operably connected with the selected roll. The depositing of the coin was 35 adapted to close the motor circuit and thereby set in motion the means that selected and operated said roll.

This invention relates more particularly to 40 the provision of a structure that embodies

common means operated by each train of coin controlled devices for effecting the closing and opening of the motor circuit, means that are individual to each of said train of devices for selecting and starting the playing of the particular roll or rolls desired, and means whereby a plurality of selections may be registered and the corresponding musical numbers played or re-played without interrupting the operation of the instrument. 55

Other objects and advantages of my invention, together with a more complete understanding of the same, may be obtained from the following detailed description and the claims taken in connection with the accompanying drawings, in which—

Figure 1 is a top plan view of the starting and selecting mechanism of my invention;

Figure 2 is a longitudinal sectional view taken on line 2, 2, Figure 1, looking in the 70 direction indicated by the arrows;

Figure 3 is a vertical transverse sectional view taken on line 3, 3, Figure 2, looking in the direction indicated by the arrows;

Figure 4 is a view similar to Figure 3, taken 75 on line 4, 4, of Figure 1, looking in the direction indicated by the arrows;

Figure 5 is a diagrammatic view, illustrating an operative connection of the starting and selecting mechanism with the motor circuit and the music roll selecting mechanism of a motor-driven automatic musical instrument, such as a pneumatically operated player-piano; and

Figures 6, 7, 8, 9 and 10 are detail views of 85 parts shown in Figure 5, the first four being taken, respectively, upon the lines 6—6, 7—7, 8—8 and 9—9 of said figure.

Referring more particularly to Figs. 1 to 90 4 of the drawings, it will be seen I have provided a channel-shaped supporting-frame having a base-plate 5 to which, by means of brackets 6 and 7, the vertical side walls 8 and 9, respectively, are secured. For convenience in describing, the right hand end of the base, as seen in Figure 2, will be termed the forward end, and the left hand end referred to as the rearward end. At the forward end of the base 5, a bank or series 10 of coin chutes are provided, con- 95 100

sisting of a plurality of vertically disposed cast tubular chutes 11 that are rectangular in cross-section and have flared mouths 12 at their upper ends to receive a coin, and 5 open lower ends from which the coins deposited therein discharge into a suitable coin receptacle (not shown). Each of the chutes 11 is provided with rearwardly and forwardly extending perforated ears 13 and 14 10 and, when said chutes are assembled, these ears are arranged in alignment to receive transverse bolts or rods 15 and 16, respectively, which latter are anchored in the side walls 8 and 9 by other suitable means, such 15 as nuts 17, to retain said chutes in the position shown in the drawings.

A knife-blade switch for closing and opening the motor circuit is, preferably, secured to a suitable pedestal 18 of insulating material, and this pedestal is mounted on the base-plate 5 of the channel-shaped supporting-frame midway between the side-walls 8 and 9 thereof. The stationary terminal blades 20 and 21 of this switch are secured 20 to said pedestal and arranged in aligning pairs with their free ends upturned and spaced apart, and the movable blade 24 of said switch is suitably secured to and extends from one end of a rocker-bar 25 that 25 is pivoted about midway its length, at 26, to a standard 27, mounted upon the base-plate 5 of the supporting-frame. Suitable insulating washers 30 and screws 31 rigidly secure the blade 24 to bar 25, and a helical 30 spring 32 connects said bar to the base of the standard and acts, when permitted, to draw the movable blade into contact with the stationary blades of said switch.

Toggle mechanism is employed for maintaining the switch normally open in the position shown in Figure 2. This mechanism comprises a rearwardly projecting lever 33, secured by screw 34 to a tubular transverse shaft 35, which latter extends through wall 40 45 8 for connection with mechanism which will presently be referred to more particularly.

The free end of lever 33 has an upwardly extending link 38, pivotally connected thereto, and the upper end of link 38 is in turn 50 pivoted to lever 40, the forward end of which is fulcrumed to the top of the standard 27. Lever 40 carries a pawl 42 which is pivoted thereto at 43 substantially, at its center of length. This pawl 42 is provided with a 55 notch 44 in the rear corner of its lower end, and this notch is adapted to engage a suitable lug 45 that projects laterally from the rear end of the rocker-bar 25. A helical spring 46 connects lever 40 with base 5 of the supporting frame, for the purpose of normally maintaining the same in the position shown in Figure 2.

The upper end of the pawl 42 is pivotally connected at 48 to a longitudinally extending rod 49, that extends forwardly and has

its opposite end connected to the upper end of an oscillating lever 50, which latter is pivoted at its center of length on a transverse bar 51, the ends of which bar are suitably mounted on the side-walls 8 and 9, at the 70 rear of the series of coin-chutes.

The lower portion of oscillating lever 50 engages and lies against the transverse horizontal portion 52 of a U-shaped motion-transmitting yoke or frame 53, the upper ends 54 of the vertical portions of which are bent laterally and journaled in side-walls 8 and 9. This yoke 53 serves to transmit motion from mechanism to be described, when a coin is deposited in one of the chutes, to lever 50 and, through the medium of rod 49, said lever imparts motion to the pawl 42, to release the movable blade of the motor-switch and permit it to engage the stationary blades and close the switch.

There is a transversely arranged series 55 of coin controlled detents which are identical in construction and operation, and operate independently of one another, therefore a description of but one will suffice. As best 90 shown in Figure 2, each detent preferably comprises a plate 56 pivotally mounted at 57 between spaced ears 58 that project rearwardly from the lower portion of each of the chutes 11. The shape of this plate is roughly suggestive of a bird's head in side view. The pivotal pin of the detent intersects the eye of said head, and the forwardly projecting finger 60 represents the bill thereof and projects through a vertically elongated slot 95 in the lower portion of the rear wall of the respective coin-chute into the passage or throat of the chute. This finger is engaged by the coin as it gravitates downwards and its upper edge is curved to facilitate the passage of the coin into the coin receptacle (not shown). A vertical arm 62 is formed on detent plate 56 and extends vertically therefrom when the detent is in its normal position, as shown in Figure 2.

The detent serves to control both the switch releasing mechanism and the selective and restoring mechanism, these mechanisms being controlled through the release of one of the bell-crank levers 63 (of which there is one for each detent), mounted in parallel relation on a transverse rod 64, which latter is carried in a suitable transversely extending abutment 65 on base 5, which abutment has a plurality of notches 66, each receiving one of said bell-crank levers. As these levers are alike, a description of but one will suffice. The forwardly extending horizontal arm 67 of each bell-crank lever normally rests upon the vertical arm 62 of its complemental detent, and is maintained thereby against the tension of a helical spring 68, which latter is connected at one end to the depending arm 69 of said lever and has its other end anchored to a transverse rod 70 fixedly secured to the 100 105 110 115 120 125 130

side walls 8 and 9 of the supporting-frame. These levers 63 are each provided with a vertical extension 71 near their fulcrums, and these extensions are each connected at 72 to a rearwardly extending rod 73 that directly connects them to the selective and restoring mechanism to be presently described. The extension 71 of each lever 63 lies to the rear of and against the horizontal portion 52 of the frame 53, so that, when one of the detents is tripped by a coin, the extension 71, acting under the tension of the spring 68, will impart a forward movement to the lower end of lever 50 through the U-shaped frame 53 and thus actuate the pawl 42 to release the switch and permit the same to close.

The forward motion of the extension 71 causes rod 73 to move forward, which latter is connected to one of a plurality of depressible selective abutment pawls 74. These pawls correspond in construction and operation, are disposed in a transverse series, and are complementary in number and arrangement to the detents and bell-crank levers, and each of said pawls 74 is pivoted at its lower end to one end of a vertically oscillatable lever 75, the opposite end of which is fulcrumed upon a stationary transverse shaft 76 carried by side walls 8 and 9. The shanks 50 of the pawls 74 extend through equi-distant slots 77, arranged in a transversely mounted plate 78, the pawls having enlarged heads on their upper ends 79 that are engaged and depressed, in a manner to be described, by adjustable selective pins 80 mounted in and extending radially from the drum 81, which latter is mounted upon a suitable revolvable shaft 82 journaled in the side walls 8 and 9 of the supporting frame. The drum is provided with a circumferential groove 81' to accommodate the passage of rod 49. Pins 80 are arranged helically about the cylindrical face of the drum, there being a pin corresponding to each detent. The pawls 74 and coacting levers 75 are maintained at the upper limits of their movement, as shown best in Figure 2, by helical springs 83 that connect levers 75 to a rod 83^a mounted in the side walls 8 and 9. A transverse rod 84, mounted 50 in the side walls, limits the upward movement of the levers 75 and pawls 74.

Immediately beneath the shaft 76 is a transverse rock-shaft 85 that is journaled in side walls 8 and 9. Between its bearings said rock-shaft is crank-shaped or U-shaped so as to provide a portion 86 that extends beneath the levers 75. This portion 86 is adapted to be engaged and depressed by said levers when the latter are depressed, thus imparting partial rotation to said shaft 85. At one end an L-shaped arm 87 is carried by shaft 85, and this arm is connected through a link 88 with the upper end of a lever 89 carried by and projecting from a shaft 90, which is journaled in the side wall 9 of the supporting

frame and extends through tubular shaft 35. A coil spring 91, anchored at 92 to base 5, is connected to said lever 89 and normally tends to maintain the same in the vertical position shown in Figure 2.

Referring, now, to Figures 5 to 10, inclusive, wherein I have shown, diagrammatically and for illustrative purposes only, an operative connection of the just-described starting and selecting mechanism with the motor circuit and the music roll selecting mechanism of a motor-driven, pneumatically operated, automatic musical instrument, it will be seen that the frame 93 carries a plurality of music rolls 94 and is rotatable by the central shaft 95 to bring the different rolls successively, or otherwise, into position for operative relation with the tracker bar 96. Tracker bar 96 is supported by links 97-97 and bell-crank 98-98 for reciprocative movement into and from operative contact with the music sheets carried upon the several rolls 94. As is well known, in pneumatically operated, automatic musical instruments of this character, the music sheets are provided with perforations designed to cooperate with a row of apertures in the tracker bar, each tracker bar aperture opening into a separate flexible tracker-tube, two of which are shown at 99, through which the operations of the respective valve-actions of the instrument are controlled by the opening and closing of the tracker bar apertures as the perforated music sheets are propelled thereacross. One of such valve-actions is shown at 100.

A pump 101 is driven, by a belt 102, from an electric motor 103 to exhaust air, through a conduit 104, from the chamber 105 which is common to all the valve-actions, such as 100, communicating therewith through passages and pin-hole-vents, such as 106 and 107, respectively. Each valve-action 100 comprises a double-ported valve-chamber 108, a diaphragm-chamber 109, an intermediate air-chamber 110, a valve 111, and a diaphragm-pneumatic 112. The outer port 113 of chamber 108 communicates with the atmosphere, the inner port 114 thereof with chamber 110, and the head of valve 111 is positioned in chamber 108 to play between and alternately open and close ports 113 and 114 under the control of diaphragm-pneumatic 112, which forms a flexible air-tight wall between chambers 109 and 110 and is in turn controlled, in the usual manner by the alternate admission and exclusion of atmospheric air to and from the respective tracker-tube 99 and chamber 109. For the purposes of this description, I have shown valve-chamber 108 connected, through a conduit 115, with a power-pneumatic 116, the office of which will be later described, but the control and operation thereof is just the same as that of any one of the usual action-pneumatics, one of

which is shown at 117 with its connecting conduit 118. I have likewise shown diaphragm-chamber 109 connected, through a tube 119, with an atmospheric inlet valve-device 120, the office and operation of which will also be later described, but the admission and exclusion of atmospheric air to and from chamber 109 through this tube 119 controls the operation of valve-action 100 in exactly the same manner as the various other valve-actions are controlled through their respective connections 99 with the tracker bar apertures. When air is exhausted from chamber 105, it will also be exhausted, through passage 106, from chamber 110 and, through pin-hole-vent 107, from chamber 109 and, if the respective tube 119 is sealed against the admission of atmospheric air, the degree of exhaust will be the same upon both sides of diaphragm-pneumatic 112, and valve 111 will be sucked tightly over inner port 114, leaving outer port 113 open to admit atmospheric air to chamber 108, conduit 115, and power-pneumatic 116.

Considering, now, the usual music sheet control of the action-pneumatics, when a music sheet perforation registers with a corresponding tracker bar aperture, atmospheric air passes therethrough to the respective tracker-tube 99 and chamber 109 in greater volume than can be withdrawn through pin-hole-vent 107, thereby weakening the exhaust acting in chamber 109 upon the adjacent side of diaphragm-pneumatic 112. The area of said diaphragm-pneumatic being greater than that of port 114, the exhaust in chamber 110 instantly sucks the diaphragm-pneumatic inwardly and thereby pushes the head of valve 111 away from inner port 114 and seats it over outer port 113. Action-pneumatic 117 is thereupon collapsed by the exhaustion of air therefrom, through conduit 118, valve-chamber 108, and inner port 114, and through its collapse causes the sounding of the respective note, or the operation of any other device which it may be designed to actuate under the control of the music sheet. Upon the passing of the music sheet perforation and the closing of the tracker bar aperture by an imperforate portion of the sheet, the former degree of exhaust is immediately reestablished in chamber 109, through pin-hole-vent 107; the balance of diaphragm-pneumatic 112 is thereby restored; valve 111 is instantly sucked inwardly to again cover port 114 and open port 113; and action-pneumatic 117 is permitted to expand, all in the usual well known manner.

Drive-shaft 121 of pump 101 is connected, by sprocket-and-chain gearing 122, with shaft 123, which carries, fast thereupon, the driving member 124 of a clutch 125 to be presently described. Shaft 123 is connected, through bevel-gearing 126, shaft 127, and sprocket-and-chain gearing 128, with the driving member 129 of another clutch 130, the driven member 131 of which is connected, by belt 132, with a large pulley 133 fast upon the central shaft 95 of the rotatable music-roll-carrying frame 93. The connection of driving member 129 with driven member 131 and, consequently, the rotation of frame 93, is controlled by a lever 134 which is connected, by a tie-rod 135, with bell-cranks 98-98, so that the driving of the rotatable music-roll-carrying frame 93 will stop simultaneously with the movement of tracker bar 96 toward its operative position in contact with one of the music sheets carried upon the several rolls 94 (see Fig. 10).

Clutch 125 comprises a driven member 136 which is fast upon a shaft 137 and carries a spring-pressed, pivoted clutch-dog 138, the spring (not shown) acting to swing the clutch-dog radially outward into the path of several clutch-pins 139 carried upon the adjacent face of driving member 124. A loose sleeve 140, having a beveled head 141, is mounted to slide upon shaft 137 and is adjustably engaged by a control-lever 142, so that, when the lever is moved to slide the sleeve along the shaft away from driving member 124, the beveled head 141 will engage the heel of clutch-dog 138 and swing the point thereof radially inward out of the path of clutch-pins 139.

Shaft 137 is connected, by worm-gearing 143, with a cam-shaft 144 having four cams 145, 146, 147 and 148 fixed thereupon. Cam 145 is provided with two diametrically opposite shoulders 149 and 150 (see Fig. 6) which engage with a stud 151 upon a link 152, which link is pivotally connected at 153 with control-lever 142 and is urged toward cam 145 by a spring 154. The end of control-lever 142 distant from the end engaging loose sleeve 140 is provided with a lateral slot 155 which is transfixed by a fixed pivot-stud 156, and, at a point between said slotted end and the pivotal connection 153, said control-lever 142 is engaged by a spring 157 which acts upon said control-lever in opposition to the action thereupon of link 152. Shaft 90 of the starting and selecting mechanism carries an arm 158, and the movable side of power-pneumatic 116 carries an arm 159, each of which arms are arranged to act upon the free end of link 152 to move it away from cam 145, in opposition to the action of spring 154, and effect the disengagement of stud 151 from either of the shoulders 149 or 150. As will be later apparent, the actions of arms 158 and 159 are momentary.

Whenever the aforesaid disengagement of stud 151 from either of the shoulders 149 or 150 occurs, spring 157 is thereby permitted to swing control-lever 142 upon pivot-stud 156 and slide loose sleeve 140 toward driving member 124, moving beveled head 141 to allow clutch-dog 138 to swing into the path of

of clutch-pins 139. This throwing in of clutch 125 effects a half-turn of cam-shaft 144 and cam 145, at which point it is automatically thrown out again through the engagement of stud 151 by the shoulder on cam 145 which is diametrically opposite thereon to the one just disengaged. As this shoulder engages the stud and moves link 152, it thereby effects the clutch-disengaging movement of the connected control-lever 142. Due to the friction between clutch-dog 138 and the clutch-pin 139 engaged thereby, the slotted end of control-lever 142 will be first moved, against the action of spring 157, until the end 15 of the slot 155 encounters pivot-stud 156, upon which the control-lever will then pivot and, upon its continued movement, the other end thereof will slide loose sleeve 140 away from driving member 124, bring the beveled head 141 again into engagement with the heel of clutch-dog 138 and force the point thereof radially inward out of engagement with the clutch-pin 139. This throwing out of clutch 125 instantly stops the disengaging movement, and the arrangement of slot 155 is to insure proper clearance between the clutch-dog and clutch-pins. The disengagement of clutch-dog and clutch-pin permits spring 157 to return the slotted end of control-lever 142 20 to its normal position, swinging it upon pivotal connection 153 as far as the length of slot 155 will permit, and sliding loose sleeve 140 still further away from driving member 124, so that the point of clutch-dog 138 will 25 be still further withdrawn from the path of clutch-pins 139.

Cam 146 is a single-drop cam (see Fig. 7) which acts upon a projection 160 on a lever 161, one end of which lever is pivotally fixed 30 at 162 and the other end connected, by a link 163, with an arm 164 fixed upon tubular shaft 35. Cam 147 is a smooth-faced eccentric (see Fig. 8) which acts upon one end-part of a rocker-lever 165, the opposite end-part of 40 which is arranged to operate a flap-valve 166 and thereby control the admission and exclusion of atmospheric air to and from a conduit 167 which is connected with conduit 104. When open, valve 166 renders pump 50 101 ineffective to reduce the air-pressure in chamber 105, and valve-actions 100 will be inoperative. Cam 148 is also a smooth-faced eccentric (see Fig. 9) and acts within a rectangular yoke 168 carried at one end of a tie-rod 169, the other end of which is pivotally connected at 170 with one of the bell-cranks 55 98-98. This cam 148 effects the positive movement, in each direction, of tracker bar 96 and the driving member 129 of clutch 130. 60 The shaft 82, previously referred to, is connected, by sprocket-and-chain gearing 171, with central shaft 95, whereby drum 81 is caused to operate in synchronism with the rotatable magazine or otherwise operable 65 frame 93 carrying the plurality of music rolls

94, so that the mechanism of the particular coin chute in which the coin is deposited determines which pawl 74 will be depressed by its complementary pin on the drum 81 and which one of the plurality of music rolls shall 70 be played.

In operation when a coin is deposited in one of the coin chutes, for example, that designated A, it trips the detent of the coin chute and releases one of the bell-crank levers 75 63 complementary to said coin chute. This automatically imparts movement to the oscillating lever 50, which latter, in turn, trips the pawl 42 (through the medium of rod 49) and releases the switch blade, permitting the 80 same to close the motor circuit 174 (see Fig. 5) and start the instrument. Electric motor 103 now drives the pump 101 and the two driving members 124 and 129 of the respective clutches 125 and 130. At this initial 85 stage of the operation, valve 166 is open and the pump is therefore ineffective, as previously described; clutch 125 is held thrown out of engagement; tracker bar 96 is in retracted position, clear of music rolls 94 and their 90 supporting frame 93; and clutch 130 is engaged. Consequently, the starting of the instrument first causes the rotation of the music-roll-carrying frame 93 and the synchronous rotation of drum 81 in the direction of the arrow a, shown in Figure 2, and the rocking movement of the bell-crank lever 63 automatically shifts the coacting selective pawl 74 into the path of movement of the complementary pin on the drum. The drum rotates as the roll of music to be played is being moved into position, and when the said roll 95 nears its proper position for cooperation with the tracker bar, the pin on the drum engages the respective selective pawl of the co-operating set of selective mechanism and imparts motion to the shaft 90 through shaft 85, arm 87, link 88, and lever 89. The motion of the shaft 90 swings arm 158 (see Figs. 5 and 6) and presses link 152 to disengage stud 151 100 from shoulder 149, allowing spring 157 to swing control-lever 142 and thereby throw in clutch 125, upon which, cam-shaft 144 makes its first half-revolution and stops, in the manner already described. This first 105 half-revolution of cams 146, 147 and 148 results in the following shifting of the several mechanisms controlled thereby. Cam 146 presses lever 161 and the connected arm 164 110 to effect a partial rotation of shaft 35, sufficient to raise and hold the lever 33, link 38, lever 40, and pawl 42 in the dotted line position shown in Figure 2. Cam 147 releases its pressure upon rocker-lever 165 sufficiently to 115 allow flap-valve 166 to close and permit pump 101 to reduce the air-pressure in chamber 105 for the actuation of valve-actions 100, and cam 148 acts upon rectangular yoke 168 to 120 throw out clutch 130 and move and hold tracker bar 96 in operative contact with the 125 130 frame 93 carrying the plurality of music rolls

selected music sheet. Upon the disengagement of clutch 130, the rotation of music-roll-carrying frame 93 and drum 81 ceases, with the selected music roll in proper playing position, and, as tracker bar 96 is moved into contact with the music sheet, valve-device 120 is also permitted to move into contact therewith. Means (not shown) for propelling the music sheet is brought into operation at this time, and the instrument will play the tune represented by the selected music roll in the usual manner. Simultaneously with the aforesaid motion of shaft 90, the bell-crank lever 63 is restored to the position shown in full lines in Figure 2. This action is brought about by the action of the cam face 79^a on the face of the pawl which bears against the forward end wall of its complemental slot in the plate 78. This cam produces a rearward movement of the upper end of the pawl 74 as the pawl is depressed and, pulling rearwardly upon the rod 73, raises the horizontal arm 67 of the bell crank lever 63, against the tension of the spring 68, to its normal position shown in full lines in Figure 2. At the same time the cam carries the head 79 of the pawl 74 out of the path of its complemental pin 80 on the drum 81. When the bell crank lever 63 has been restored to normal position as just described, the oscillating lever 50 is permitted to resume its normal position and bring the pawl 42 into engagement with the rocker-bar 25 of the switch by virtue of the lateral extension formed thereon. The weighted end 59 of the detent 55 restores this part to normal position, as shown in Figure 2, immediately that the horizontal arm 67 of the bell crank is elevated sufficiently for the vertical arm 62 of the detent to pass beneath the same. Just prior to the stopping of drum 81, the depression of the abutment pawl 74 causes its withdrawal and release from the complemental pin 80 in the manner heretofore described, and the pawl is restored, by the action of the spring 83, to the position shown in full lines in Figure 2. When the playing of the selected roll has been completed, a hole provided in the respective music sheet moves into registration with the trailing finger 172 of valve-device 120 (see Fig. 10), whereupon valve 173 opens and admits atmospheric air to tube 119, resulting in the collapse of power-pneumatic 116, in the manner heretofore described. This collapse of power-pneumatic 116 acts, through arm 159, to press link 152 and disengage stud 151 from shoulder 150, and the second half-revolution and stopping of cam-shaft 144 is effected in the same manner as that described in connection with the first half-revolution thereof. This second half-revolution of cams 146, 147 and 148 returns the parts actuated thereby to their original positions. Cam 147 effects the opening of flap-valve 166, and cam 148 moves tracker bar 96 and valve-device 120 into their positions away from music rolls 94

and frame 93, and effects the re-engagement of clutch 130. The drop on cam 146 passes the projection 160 on lever 161 and allows spring 46 (Fig. 2) to return lever 161 and arm 164 to their positions shown in Figure 7, 70 and to restore levers 33 and 40 to their full-line positions shown in Figure 2, thus raising the switch-blade 24 and breaking the motor circuit 174, unless prevented from so doing in the manner to be now described.

After the first coin has been deposited and the playing of the desired selection has begun, another coin may be deposited in the same chute, if desired, to effect the re-playing of the same selection. The beginning of the 80 playing of a selection is an indication that the respective coin controlled selecting mechanism has been restored to its original position, since the hereinbefore described depression, withdrawal, and restoration of a selective pawl 74 initiates the playing operation and simultaneously effects the restoration and re-latching of the respective coin controlled selecting mechanism. The deposit of a second coin in the same chute, after the playing 90 of the respective selection begins, therefore acts as an initial operation of the respective selecting mechanism.

It is to be noted that coins may be deposited in any or all of the several chutes, thereby tripping any or all of the detents and displacing their respective pawls 74, and it follows that, when a number of pawls are in such displaced position, the pawl first to be encountered by its complemental pin 80 in the rotation of drum 81 will effect the playing of the corresponding musical selection and the restoration of the respective selecting mechanism. So long as any of the pawls 74 remain in the path of their complemental pins 80, the corresponding bell-crank levers 63 will remain in tripped position and prevent the lever 50 from assuming its normal position, to the effect that pawl 42 will miss lug 45 when the pawl is moved downwardly 100 at the completion of the playing of a roll. The different rolls will be played and the corresponding selecting mechanisms will be restored in the order in which the pins 80 encounter and depress the selectively displaced pawls 74, and it follows that a roll may not be immediately re-played if pawls for other selections are in displaced position. It has been mentioned that the operation of a pawl includes its depression, withdrawal, release, and restoration (to the full-line position shown in Fig. 2). If immediately displaced again, it would be necessary for the drum to make a complete revolution in order to re-engage the same pawl and repeat its 110 operation and, if other pawls were in displaced position, they would be encountered by their complemental pins before such complete revolution of the drum could be effected.

While a specific mechanical arrangement 130

and adaption of the invention has been illustrated, and described, I reserve the right to employ the invention in other capacities and make minor changes therein within the spirit of the invention and scope of the claims.

5. What I claim as new is:

1. In a controlling mechanism for motor driven musical instruments, an electric switch controlling the circuit to the motor of said instrument, means normally acting to close 10 said switch, means for holding said switch in open position, a motor driven member, coin controlled mechanism for releasing the switch holding means, means controlled by the motor driven member for placing the 15 switch holding means in position to open the switch, and means for actuating the holding means for opening the switch and stopping the motor.

2. In a controlling mechanism for motor 20 driven musical instruments, an electric switch controlling the circuit to the motor of said instrument, means normally acting to close said switch, means for holding said switch in open position, a motor driven member, coin controlled mechanism for releasing the switch holding means, means controlled by the motor driven member for placing the 25 switch holding means in position to open the switch, and means for actuating the holding means for opening the switch and stopping the motor, together with means operated by the motor driven member for causing the coin controlled mechanism to be restored 30 to normal.

3. In a controlling mechanism for motor operated musical instruments, the combination of a switch for controlling the circuit of the motor, coin controlled means for closing 35 said switch, means for opening said switch which comprises in part a motor actuated member and a pawl moved thereby, and means actuated by the pawl for restoring said coin-controlled means to normal position.

4. In a controlling mechanism for motor operated musical instruments, the combination of a switch for controlling the circuit of the motor of said instrument, coin controlled mechanism for closing said switch, 50 means for opening said switch comprising in part a motor operated rotatable element having studs and pawls arranged to lie in the path of said studs upon operation of said coin controlled mechanism, said pawls including means whereby they are automatically thrown out of the path of the respective studs and effect the restoration of said coin controlled mechanism to inoperative position.

5. In a controlling mechanism for motor operated musical instruments, the combination of a switch for controlling the circuit of the motor of said instrument, coin controlled mechanism for closing said switch,

means for opening said switch comprising in part a rotatable motor driven element having radiating studs, said coin controlled mechanism including coin actuated detents, pawls adapted to be placed in the path of said studs upon the actuation of said detents, whereby the rotation of said element will partially actuate said switch-opening means, and means controlled in the movement of said pawls by said element for restoring 75 said detents.

6. In a controlling mechanism for motor operated musical instruments, the combination of a switch for controlling the circuit of the motor of said instrument, coin controlled mechanism for closing said switch, means for opening said switch comprising a pawl having a cam thereon, said coin controlled mechanism including a coin controlled detent, and a motor operated element arranged 80 to engage the pawl to partially actuate said switch opening means and to restore said detent.

7. The combination with an electric motor for operating a mechanical musical instrument adapted to play from a plurality of rolls to be selected, of a spring closed switch in circuit of the motor, selective coin controlled detents, means controlled by said detents for releasing the switch to closed position, selective control mechanism operated by the motor, comprising a revolving element provided with staggered pins and a series of abutment members complementary to said detents, means for opening the switch operated 90 in part by said selective control mechanism, and means for permitting the detents to assume normal position.

8. The combination with an electric motor for operating a mechanical musical instrument adapted to play from a plurality of rolls to be selected, of a spring closed switch in circuit of the motor, selective coin controlled detents, means controlled by said detents for releasing the switch to closed position, selective control mechanism operated by the motor, comprising a revolving element provided with staggered pins and a series of abutment members complementary to said detents, means for opening the switch operated 105 in part by said selective control mechanism, and means directly connected with and operable by said abutment members for permitting the detents to assume normal position.

9. The combination with a mechanically operated musical instrument and an electric motor for driving the same, of a spring closed switch in the motor circuit, means for retaining said switch in open position, a plurality of coin controlled detents, means connected 115 with said detents for actuating said switch retaining means to release the switch to closed position when a coin is deposited, a revolving element operated by the motor and having a plurality of projections comple- 125

mental to said detents, a plurality of movable abutment members complementary to said projections for selective engagement therewith, means connecting said abutment members directly with said detents, and means for opening the switch also connected with said abutment members.

10. The combination with a mechanically operated musical instrument and an electric motor for driving the same, of a spring closed switch in the motor circuit, means for retaining said switch in open position, a plurality of coin controlled detents, means connected with said detents collectively for actuating said switch retaining means to release the switch to closed position when a coin is deposited, a revolving element operated by the motor and having a plurality of projections thereon complementary to said detents, a plurality of movable abutment members complementary to said projections for selective engagement therewith, means selectively connecting each detent to one of said abutment members, and means connected with all of said abutment members collectively for opening the switch.

11. The combination with an electric motor for operating a mechanical musical instrument adapted to play from a plurality of rolls to be selected, of a spring closed switch in circuit with said motor, selective coin controlled detent means comprising a plurality of coin slots, each having a coin-actuable detent therein, a pawl for maintaining the switch in open position, means connecting said pawl with said detent means to actuate the pawl and release the switch to closed position when a coin is deposited, a rotatable member driven by the motor and provided with a plurality of selective projections, a plurality of movable abutment members selectively operable by said projections, means connecting each of said abutment members with one of said detent means, and means for opening the switch connected through a loose connection with said abutment members.

12. In controlling mechanism for an automatic musical instrument adapted to play from a plurality of music rolls, the combination of coin-controlled means operating upon the deposit of a coin to start the operation of said instrument and selectively determine which of said rolls shall be employed in the playing thereof, restoring means operating to restore said coin-controlled means to its original condition, and stopping means operating to stop the operation of said instrument; said restoring means being automatically operated at the time the selection of the desired roll shall have been accomplished, and said stopping means being automatically operated at the time the employment of the selected roll shall have been completed.

13. In controlling mechanism for an auto-

matic musical instrument adapted to play from a plurality of music rolls, the combination of coin-controlled means operating upon the deposit of a coin to start the operation of said instrument and selectively determine which of said rolls shall be played thereupon, restoring means operating to restore said coin-controlled means to its original condition, and stopping means operating to stop the operation of said instrument; said restoring means being automatically operated prior to the playing of the desired roll, and said stopping means being automatically operated after the playing of said roll.

14. In controlling mechanism for an automatic musical instrument adapted to be controlled in operation by a plurality of music rolls, the combination of coin-controlled means operating upon the deposit of a coin to start the operation of said instrument and selectively determine which of said rolls shall be employed to control the operation thereof, means operating automatically upon the starting of the operation of said instrument to effect the selection of the desired roll and to restore said coin-controlled means to its original condition upon the effecting of such selection, and means operating automatically upon the completion of the employment of the selected roll to stop the operation of said instrument.

15. In controlling mechanism for an automatic musical instrument adapted to play from a plurality of music rolls, the combination of coin-controlled means operating upon the deposit of a coin to start the operation of said instrument and register the selection of one of said rolls, means operating automatically upon the starting of the operation of said instrument to effect the employment of one of said rolls according to the registered selection and simultaneously restore said coin-controlled means to its original condition, and means operating automatically upon the completion of the employment of the selected roll to stop the operation of said instrument.

16. In controlling mechanism for an automatic musical instrument adapted to play from a plurality of music rolls, the combination of coin-controlled means operating to start the operation of said instrument and register the selection of one of said rolls, said means comprising a releasable detent released by the deposit of a coin and a selective element displaced by the release of said detent, means operating automatically upon the starting of the operation of said instrument to actuate said element and thereby effect the selection of one of said rolls and the restoration of said element and said detent to their original positions, and means operating automatically after the completion of the playing operation of said instrument to stop the operation thereof.

17. In controlling mechanism for an automatic musical instrument adapted to play from a plurality of music rolls, the combination of coin-controlled means operating to start the operation of said instrument and selectively effect the playing of one of said rolls thereupon, said means comprising a releasable detent released by the deposit of a coin and a selective element displaced by the release of said detent, means operating automatically upon the starting of the operation of said instrument to co-operate with said element in effecting the selection and playing of one of said rolls, and to effect the restoration of said element and said detent to their original positions upon the effecting of such selection, and additional means operating automatically after the playing of said roll to stop the operation of said instrument. 70
18. In controlling mechanism for an automatic musical instrument, the combination of a plurality of coin slots, coin-controlled means individual to said slots operating upon the deposit of a coin in any of said slots to start the operation of said instrument, means operating automatically at different intermediate stages in the operation of said instrument to successively restore such of said coin-controlled means as have been operated to their original condition, and means operating automatically to stop the operation of said instrument at the final stage in the operation thereof after all of said coin-controlled means have been restored as aforesaid. 80
19. In controlling mechanism for an automatic musical instrument adapted to play from a plurality of music rolls, the combination of a plurality of coin slots individual to each of said plurality of rolls, coin-controlled means individual to each of said plurality of slots operating upon the deposit of a coin in any of said slots to start the operation of said instrument and to register the selection of any of said rolls, corresponding in number and identity to the slots in which coins have been deposited, means operating automatically upon the starting of the operation of said instrument to successively effect the selection of the desired rolls according to the registered selections and to successively restore such of said coin-controlled means as have been operated to their original condition upon the effecting of each respective selection, and means operating automatically to stop the operation of said instrument at the final stage in the operation thereof after all of said coin-controlled means have been restored as aforesaid and after all of the selected rolls have been played. 90
20. In controlling mechanism for an automatic musical instrument, the combination, with starting means operating to start the operation of said instrument, of releasable latching means acting upon release to effect the operation of said starting means, restoring means operating to effect the re-latching of said latching means, and stopping means operating to stop the operation of said instrument; said restoring means being automatically operated at an intermediate stage in the operation of said instrument, and said stopping means being automatically operated at the final stage in the operation of said instrument; and the operation of said restoring means and said stopping means being separately controlled. 95
21. In controlling mechanism for an automatic musical instrument adapted to play from a plurality of music rolls, the combination, with starting means operating to start the operation of said instrument, of releasable latching means acting upon release to effect the operation of said starting means and selectively determine which of said rolls shall be employed in the playing thereof, restoring means operating to effect the re-latching of said latching means, and stopping means operating to stop the operation of said instrument; said restoring means being automatically operated at the time the selection of the desired roll shall have been accomplished, and said stopping means being automatically operated at the time the employment of the selected roll shall have been completed. 100
22. In controlling mechanism for an automatic musical instrument adapted to play from a plurality of music rolls, the combination, with starting means operating to start the operation of said instrument, of releasable latching means acting upon release to effect the operation of said starting means and selectively determine which of said rolls shall be played thereupon, restoring means operating to effect the re-latching of said latching means, and stopping means operating to stop the operation of said instrument; said restoring means being automatically operated prior to the playing of the desired roll, and said stopping means being automatically operated after the playing of said roll. 105
23. In controlling mechanism for an automatic musical instrument adapted to be controlled in operation by a plurality of music rolls, the combination, with starting means operating to start the operation of said instrument, of releasable latching means acting upon release to effect the operation of said starting means and selectively determine which of said rolls shall be employed to control the operation thereof, means operating automatically upon the starting of the operation of said instrument to effect the selection of the desired roll and the re-latching of said latching means upon the effecting of such selection, and means operating automatically upon the completion of the employment of 110
- 130

- the selected roll to stop the operation of said instrument.
24. In controlling mechanism for an automatic musical instrument adapted to play from a plurality of music rolls, the combination, with starting means operating to start the operation of said instrument, of releasable latching means acting upon release to effect the operation of said starting means and 10 register the selection of one of said rolls, means operating automatically upon the starting of the operation of said instrument to effect the employment of one of said rolls according to the registered selection and simultaneously effect the re-latching of said latching means, and means operating automatically upon the completion of the employment of the selected roll to stop the operation of said instrument.
- 20 25. In controlling mechanism for an automatic musical instrument adapted to play from a plurality of music rolls, the combination, with starting means operating to start the operation of said instrument, of releasable latching means acting upon release to effect the operation of said starting means and register the selection of one of said rolls, said latching means comprising a releasable detent and a selective element displaced by the release of said detent, means operating automatically upon the starting of the operation of said instrument to actuate said element and thereby effect the selection of one of said rolls and the restoration of said element and said detent to their original positions, and means operating automatically after the completion of the employment of the selected roll to stop the operation of said instrument.
- 30 40 26. In controlling mechanism for an automatic musical instrument adapted to play from a plurality of music rolls, the combination, with starting means operating to start the operation of said instrument, of releasable latching means acting upon release to effect the operation of said instrument and selectively effect the playing of one of said rolls thereupon, said latching means comprising a releasable detent and a selective element displaced by the release of said detent, means operating automatically upon the starting of the operation of said instrument to cooperate with said element in effecting the selection and playing of one of said rolls, and to 50 effect the restoration of said element and said detent to their original positions upon the effecting of such selection, and additional means operating automatically after the playing of said roll to stop the operation of said instrument.
- 55 60 27. In controlling mechanism for an automatic musical instrument, the combination, with starting means operating to start the 65 operation of said instrument, of a plurality of releasable latching means each acting upon release to effect the operation of said starting means, means operating automatically at different intermediate stages in the operation of said instrument to successively effect the re-latching of such of said latching means as have been released, and means operating automatically to stop the operation of said instrument at the final stage in the operation thereof after all of said latching means have been re-latched.
- 70 28. In controlling mechanism for an automatic musical instrument adapted to play from a plurality of music rolls, the combination, with starting means operating to start the operation of said instrument, of a plurality of releasable latching means individual to each of said plurality of rolls acting upon release to effect the operation of said starting means and to register the selection of any of said rolls, corresponding in number and identity to such of said latching means as have been released, means operating automatically upon the starting of the operation of said instrument to successively effect the selection of the desired rolls according to the registered selections and to successively effect the re-latching of the respective latches as each such selection is effected, and means operating automatically to stop the operation of said instrument at the final stage in the operation thereof after all of said latching means have been re-latched as aforesaid and after all of the selected rolls have been played.
- 80 90 29. In a controlling mechanism for motor operated musical instruments, the combination of a switch for controlling the circuit of the motor of said instrument, a bodily movable latch for engaging said switch to open the same, controllable means operated through the operation of said instrument by said motor for bodily moving said latch into switch-engaging position, and optionally actuatable means for controlling the engagement of said latch with said switch.
- 95 100 30. In a controlling mechanism for motor operated musical instruments, the combination of a switch for controlling the circuit of the motor of said instrument, a bodily movable latch for engaging said switch to open the same, controllable means operated through the operation of said instrument by said motor for bodily moving said latch into and from switch-engaging position, and optionally actuatable means for controlling the engagement of said latch with said switch.
- 105 110 31. In a controlling mechanism for motor operated musical instruments, the combination of a switch for controlling the circuit of the motor of said instrument, a bodily movable latch for engaging and opening said switch, controllable means operated through the operation of said instrument by said motor for bodily moving said latch into posi-

tion to engage said switch and from said position to open said switch, and optionally actuatable means for controlling the engagement of said latch with said switch.

5 In witness whereof I have hereunto set my hand this 21st day of July, 1921.

CLIFFORD H. GREEN.
